UNITED STATES PATENT OFFICE.

GEORGE HAVILAND, OF PARIS, FRANCE, ASSIGNOR TO HAVILAND & CO. SOCIETE ANONYME, OF LIMOGES, FRANCE, A JOINT STOCK COMPANY.

DESIGN FOR A PITCHER OR SIMILAR ARTICLE.

Application filed January 10, 1928. Serial No. 24,805. Term of patent 14 years.

To all whom it may concern:

Be it known that I, GEORGE HAVILAND, a citizen of the United States, residing at Paris, France, have invented a new, original, and ornamental Design for a Pitcher or Similar Article, of which the following is a specification, reference being had to the accompanying drawings, forming a part thereof and in which:

Fig. 1 is a side elevation of the article, showing my new design;

Fig. 2 a plan, and

Fig. 3 a detail section on the line 3—3, Fig. 1.

I claim:

The ornamental design for a pitcher or similar article, as shown.

GEORGE HAVILAND.
